UNITED STATES PATENT OFFICE.

JOHN W. BROWN, OF WEST ALLIS, AND ALEXANDER J. NICHT, JR., OF MILWAUKEE, WISCONSIN, ASSIGNORS TO ALLIS-CHALMERS MANUFACTURING COMPANY, OF MILWAUKEE, WISCONSIN, A CORPORATION OF DELAWARE.

ELEVATOR BRAKE.

Application filed January 24, 1920. Serial No. 354,207.

To all whom it may concern:

Be it known that JOHN W. BROWN and ALEXANDER J. NICHT, Jr., citizens of the United States, residing at West Allis and

5 Milwaukee, respectively, in the county of Milwaukee and State of Wisconsin, have invented a certain new and useful Improvement in Elevator Brakes, of which the following is a specification.

10 This invention relates in general to an improved device for preventing reversal of a rotary shaft, and relates more specifically to an improved brake for stopping an elevator or the like in case the driving power fails.

An object of the invention is to provide a simple and efficient brake for preventing reversal of a rotating shaft or drum.

It has been found desirable in some instances, to provide hoisting apparatus such as bucket elevators, with a device for positively arresting the motion of the carriers upon failure of the driving power. If no such braking means are provided, the loaded carriers will quickly reverse their direction of travel upon failure of the driving power, thus causing serious damage and possible destruction of the elevator.

The present invention contemplates the provision of mechanism for positively preventing reverse movement of an elevator or the like. This contemplated result is accomplished by providing a stationary shaft or pivot spaced from and extending parallel to one of the rotating elements of the elevator, and connecting the rotating elevator element and the pivot by means of a toggle mechanism. During normal forward operation of the elevator this toggle mechanism is flexed. If however, for any reason the elevator tends to reverse its direction of travel, there is a resulting tendency to straighten the toggle mechanism. This tendency towards straightening of the toggle mechanism exerts braking pressure upon the rotary elevator portions thus preventing reverse movement of the elevator.

A clear conception of an embodiment of the invention and of the mode of operation of a mechanism built in accordance therewith, may be had by referring to the draw-

ing accompanying and forming a part of this specification in which like reference characters designate the same parts in the various views.

Fig. 1 is a side elevation of an elevator braking mechanism showing the approximate relative position of a bucket elevator in dot and dash lines.

Fig. 2 is an end elevation of the elevator 60 brake.

Fig. 3 is a plan view of elevator brake.

Fig. 4 is an enlarged side elevation of a portion of the brake mechanism.

Referring specifically to Figs. 1, 2 and 3, 65 the horizontal shaft 2 represents the upper shaft of a vertically disposed bucket elevator. Secured to the horizontal shaft 2 is a drum 3 with which coacts an elevator belt 4 having a series of buckets 5 secured thereto. As illustrated the elevator buckets 5 are normally adapted to travel in an anti-clockwise direction as shown by the arrow in Fig. 1, about the axis of the shaft 2 when traveling around the drum 3. Secured to the shaft 2 at one side of the bucket elevator, is a brake-wheel 6 which is rigidly attached to the shaft 2 in any suitable manner. Located laterally of the brake-wheel 6 is a stationary bracket 11 which forms a 80 support for the horizontal pivot 10 the axis of which is parallel to the axis of the rotating shaft 2. The pivot 10 and bracket 11 are connected with the shaft 2 by means of tie-pieces 7 located one on each side of the 85 brake-wheel 6. Displacement of the tie-pieces 7 longitudinally of the shaft 2 is prevented by means of the hub of the brake-wheel 6 and by means of the collars 15 secured to the shaft 2. A movable toggle link 9 is mounted upon the pivot 10 and has a downwardly projecting rear portion 12 extending along the rear face of the bracket 11. An adjusting cap-screw 13 has screw-thread coaction with the projection 12 and is engageable with the adjacent surface of the bracket 11 to limit the upward travel of the link 9 about the pivot 10 as a center. The end of the link 9 nearest the brake-wheel 6, carries a pivot 14 upon which a 100 brake-shoe 8 is mounted. The brake-shoe 8 has a facing 16 provided with a braking

surface engageable with the peripheral surface of the brake-wheel 6.

The details of construction of the link 9 and brake-shoe 8 are more clearly disclosed in Fig. 4. From the disclosure in this figure it will be noted that the brake-shoe 8 is provided with a detachable facing 16 which cooperates with the brake-wheel 6 and which may be renewed if necessary. The pivot 14 which connects the brake-shoe 8 with the toggle lever 9 is mounted in an adjustable block 17 which is slidable within the slotted end of the lever 9. An adjusting wedge 19 coacts with the block 17 and with an end 15 surface of the slot in the lever 9, the wedge 19 being movable transversely of the lever 9 to vary the position of the block 17 by means of an adjusting bolt 18. The adjusting bolt 18 may be locked in any adjusted position by means of a locking nut 20.

During the normal operation of the elevator, the brake mechanism is in the position illustrated in Fig. 1 with the connecting pin 14 above a horizontal plane passing through the axes of the shaft 2 and the pivot 10. Rotation of the bucket elevator in its normal or anti-clockwise direction tends to flex the toggle formed by the brake-wheel 6 and brake-shoe 8 as one element and the link 9 as the other element. If for any reason the is reversed, the friction between the peripheral surface of the brake-wheel 6 and the brake-shoe 8, causes the brake-wheel 6 to carry the brake-shoe 8 in a clockwise direction about the axis of the shaft 2 thereby tending to straighten the toggle connecting the shaft 2 and the pivot 10. This tendency towards straightening of the toggle, causes the brake-shoe 8 to firmly grip the peripheral surface of the brake-wheel 6 and quickly stops reverse travel of the shaft 2 and of the bucket elevator. With the brake-wheel 6 thus gripped, the tie-pieces 7 positively prevent dislocation of the bracket 11 relatively to the shaft 2.

The rate of operation of the brake may be varied by adjusting the position of the block 17 and also by limiting the clockwise movement of the lever 9 about the pivot 10 by adjustment of the cap-screw 13. The various parts of the mechanism are readily removable and are accessible at all times. While the invention has been disclosed as being specifically applied to an elevator of the bucket type, it will be obvious that the principles involved are applicable generally

wherever it is desired to prevent reverse rotation of a rotatable shaft.

It should be understood that it is not desired to limit the invention to the exact details of construction herein shown and described, for obvious modifications within the scope of the appended claims may occur to persons skilled in the art.

It is claimed and desired to secure by Letters Patent:—

1. In combination, a horizontally disposed rotary shaft, a horizontally disposed pivot spaced horizontally from said shaft, and a single toggle connecting said pivot and said shaft, one element of said toggle comprising a link and the other element comprising a brake wheel secured to said shaft and a shoe having surface coaction with said wheel, rotation of said shaft in one direction tending to flex said toggle while maintaining said surface coaction and reverse rotation of said shaft tending to straighten said toggle and stop said shaft.

2. In combination, a rotary shaft, a pivot spaced from said shaft, a tie-member directly connecting said shaft and said pivot, and a toggle located closely adjacent to said tie-member and connecting said pivot and said shaft, one element of said toggle comprising a link and the other element comprising a brake wheel secured to said shaft and a shoe having surface coaction with said wheel, rotation of said shaft in one direction tending to flex said toggle while maintaining said surface coaction and reverse rotation of said shaft tending to straighten said toggle and stop said shaft.

3. In combination, a rotary shaft, a pivot spaced from said shaft, a pair of laterally spaced tie-members directly connecting said shaft and said pivot, and a toggle located between said tie-members and connecting said pivot and said shaft, one element of said toggle comprising a link and the other element comprising a brake wheel secured to said shaft and a shoe having surface coaction with said wheel, rotation of said shaft in one direction tending to flex said toggle while maintaining said surface coaction and reverse rotation of said shaft tending to straighten said toggle and stop said shaft.

In testimony whereof, the signatures of the inventors are affixed hereto.

JOHN W. BROWN.
ALEX. J. NICHT, JR.
